UNITED STATES PATENT OFFICE.

MARIE MELOTZ, OF OMAHA, NEBRASKA.

EGG-CARRIER.

1,121,932.

Specification of Letters Patent. Patented Dec. 22, 1914.

Application filed April 11, 1914. Serial No. 831,113.

To all whom it may concern:

Be it known that I, MARIE MELOTZ, a citizen of the United States, residing at Omaha, in the county of Douglas and State 5 of Nebraska, have invented certain new and useful Improvements in Egg-Carriers, of which the following is a specification.

This invention relates to an improvement in egg carriers, and has for its principal 10 object to provide a carrier or container in which eggs may be conveniently packed or removed therefrom, and will protect them in a manner to prevent breakage when sent by mail or otherwise shipped.

Another object is to provide a carrier for 15 this purpose which will be of light weight, but of strong construction, and consisting of such parts that manufacture will be economical.

The invention includes a plurality of sack-holding frames of a suitable length, each 20 being substantially rectangular, transversely considered, and consisting of a plurality of parallel partitions maintained side-by-side in spaced relation for sustaining the 25 sacks which contain the eggs, and a hamper having a depth substantially equal to the length of the frames and provided with parallel, inwardly projecting flanges between 30 which the frames may be held, the hamper providing a shield or housing for the frames, the eggs being held in suspended relation by use of the sacks, between the partitions of said frames.

The invention consists of the novel construction, combination and arrangement of parts as described herein and claimed, and as illustrated in the drawing, wherein,—

Figure 1 is a plan view of one of the 40 frames with the sacks suspended therein and containing the eggs. Fig. 2 is an end view of a sack-holding frame, one of the recessed latches being partly raised. Fig. 3 is a side elevation of a sack-holding frame. Fig. 4 is a sectional view on line 4-4 of Fig. 1. Fig. 5 is a plan view of one of the sacks employed. Fig. 6 is a plan view of the metallic casing of the hamper to illustrate facility in its use for mounting the 45 frames with eggs therein, together with other merchandise. Fig. 7 is a view of the casing in longitudinal section. Fig. 8 is a plan view of the hamper. Fig. 9 is a side

view of the same, the cover and jacket being in section. Fig. 10 is a side view of the 55 hamper.

Referring now to the drawing for a more particular description, a plurality of sack-holding frames are provided, as the elongated frames 1 which, transversely considered, are substantially rectangular, each frame consisting of connected, parallel end walls 2 and partitions 2', all of uniform size and shape, each having inwardly convergent recesses α , with an enlarged terminal 60 part α' (Fig. 4.) formed to open on its top and bottom, and preferably having curved corners β .

In order that the end walls and partitions may be maintained parallel and at substantially uniform distances apart, spacing-bars 4 are employed and are secured at their ends to the end walls, sleeves 5 also being used and loosely mounted on the bars intermediate the end walls and partitions 2', and between 75 partitions 2'.

While I do not wish to be limited specifically to the material to be employed, comparatively thin sheets of aluminum are preferred for the metallic parts since the particular use of the device is for sending eggs by mail, and a light weight is desired. Solder not being adapted for use in connecting the partitions 2' with bars 4, the sleeves are employed, which maintain the 85 partitions substantially parallel.

Numerals 6 indicate sacks made of fabric or other suitable flexible material to provide at their ends the small balls or buffers indicated at 7, each of said sacks being open 90 between its ends to provide oppositely disposed edges c , the length of the sacks corresponding, substantially, to the length of frames 1. At 8 are indicated latches, each being formed with recesses d (Figs. 2, 4.) 95 opening on its inner edge. They are pivoted at one of their ends, as indicated at e , upon the inner sides of the end walls and partitions 2', outwardly of and adjacent to one of the recesses α . The end walls and partitions are provided with lugs or catches 9 opposite to the pivotal mounting e of the latches. As thus described, the sacks may be placed in the recesses of the end walls and partitions of a frame with their terminal buffers 7 projecting outwardly of the 100 105

end walls, and if the latches of the end walls are then swung downwardly, the outer edges thereof may be caught by the lugs 9, and the ends of the sacks will be secured in the convergent recesses *a* of said end walls. The eggs 10 may then be placed in the sacks, between the partitions, and between the end walls and partitions, and after the latches of said partitions have been closed and 5 caught by lugs 9, the eggs will be secured in the sacks and will be supported thereby in suspended relation with reference to the frame, and any chance for breakage of the eggs will be reduced to a minimum, for the 10 reason that the sacks at the ends of the eggs will be compressed in recesses *d* of the latches and in the enlarged parts *a'* of the inwardly convergent recesses *a*, said recesses coöperating to provide contracted seatings 15 for the sacks at longitudinal intervals thereof, from which, however, the sacks may be conveniently removed.

The sacks have a suitable length, so that engagement of the contracted parts thereof, 20 as described, will prevent communication to the eggs of undue shocks or vibration directed endwise of the eggs and frame, and by reference to Figs. 2 and 4 it will be seen that the rods and sleeves of the frame are 25 so disposed that any swinging movement of the eggs or sack, transversely of a frame which may occur, will not permit engagement thereof with any metallic part of the frame.

30 From the description it will be seen that the length of the sacks is a matter of some importance, so that swinging movements of the parts thereof between the partitions will be prevented. The sacks may have 35 any suitable width so that the eggs cannot move outwardly between edges *c* of the sacks after the latches have been closed.

While I have shown a sack-holding frame provided with only two partitions, it is 40 obvious that operation would be the same if additional partitions were used, and while only two recesses *a* are shown to open on the upper and lower ends of the partitions and end walls of the frame for holding two 45 pairs of sacks, the number of said recesses and the width of the frame may be increased, if desired, and operation would be the same, it only being necessary that the convergent terminals of said recesses be 50 at sufficient distances apart to cause the eggs, thus supported, to be separated adequately.

The latches are constructed of resilient material and may be manually "sprung" 55 or bent sidewise for the purpose of being caught by or released from lugs 9. It will be noted that the eggs may be conveniently removed from the frame, the operation being simply to release the latches of partitions 2'. Since each sack is provided with

edges *c* which extend between its ends, the eggs will be accessible for removal, the operation of opening the latches of the end walls not being required for this purpose; and when placing eggs in the sacks, the only latches moved are those upon partitions 2'. When it is desired to remove or replace the sacks for sanitary reasons, all of the latches may be released.

In order that the frames and eggs therein may be suitably protected when shipped, the hamper 11, substantially of square shape, is employed. It consists of a casing or container 21 provided with a suitable jacket. The bottom *f* of the casing is provided with inwardly projecting ridges or flanges 12 which intersect each other at right angles at the longitudinal axis of the casing, and inwardly projecting, parallel flanges 13 are secured upon the inner sides 25 of said casing midway between its front and back, and similar flanges 13 are also secured upon the front and back of the casing midway between its sides, said casing being of such size and proportion that the frames, above described, may be deposited therein with the end walls of said frames loosely mounted upon or engaging flanges 12 of the bottom and flanges 13 of the upright walls thereof, to prevent displacement 30 of said frames which might be occasioned by rough usage when shipped; and by reason of the construction, other articles, as indicated at 14 and 15 may be carried in the hamper or container, if desired.

100 The casing is preferably constructed of thin sheet-metal and it should be of curved form at its upright edges or corners as indicated at *g* to conform to the curvature *b* of frames 1. At *h* is indicated a pad which surrounds the upright walls of the casing, thereby tending to prevent vibrations or shocks from being communicated to its contents, and preferably an outer layer or jacket 16 of vulcanized fiber is employed 105 to cover its sides and bottom and secured to the pad by rivets 17.

A cover consisting of the metallic part 18 and a jacket 19, preferably of vulcanized fiber, is employed for excluding moisture or dust. The cover may be removably secured upon the casing by any suitable means, a strap 20 being shown for this purpose and provided with a handle 20'.

110 The height of the casing is so proportioned that the balls of fabric or buffers 7 at the ends of the frames will engage the bottom and cover to thereby prevent injury to the eggs from concussion or shocks, during shipment.

115 While I have explained the construction of the container in detail, I do not wish to be understood as limiting myself in this respect. It is obvious that the frames require a housing or protection of some kind 120

so that the eggs which they contain may be shipped in a manner to prevent external objects from entering between the partitions or plates where the eggs are supported, 5 and while other kinds of casings or containers may be employed, the above described container has been used to advantage, and they may be conveniently constructed.

10 Since the end walls 2 and partitions 2' consist of thin plates and are alike in form and size, they may be conveniently and economically constructed, and since they are of the same form, the series of recesses a 15 which open on the outer edges of the plates, when the parts of a frame are assembled, will be disposed in alinement.

Having fully described the several parts of the invention, a further explanation relating to operation is not necessary.

What I claim and desire to secure by Letters Patent is,—

1. An egg carrier, comprising, in combination with a container provided with interiorly projecting flanges, a plurality of frames adapted to engage said flanges for a removable mounting in said container, each frame consisting of a plurality of substantially rectangular plates provided with 25 inwardly convergent recesses, a plurality of rods traversing the plates for connecting them side-by-side, members interposed between said plates and carried by said rods for sustaining the plates in spaced relation, 30 a plurality of elongated sacks disposed in said recesses to provide holders for the eggs between the plates, each of said sacks having opposed edges defining an opening extending its entire length, and a latch mounted on each plate for making engagement 40 with the sacks in said recesses.

2. An egg carrier comprising, in combination with a container, a plurality of frames adapted to be removably mounted in the container, each frame consisting of a pair of end plates, intermediate plates, said plates being provided with lugs and having recesses opening on their edges, a plurality of rods traversing the intermediate plates and connected with the end plates, members interposed between the plates and circumscribing the rods for maintaining said plates substantially parallel side by side in spaced relation, a plurality of elongated sacks, each 55 having opposed edges extending approximately its entire length, said sacks being adapted to be disposed in said recesses to provide holders therebetween for the eggs, and a latch mounted on each plate adapted 60 to have an inward swinging movement for engaging a lug to prevent removal of the sacks from said recesses, and adapted to have an outward swinging movement for permitting removal of the sacks from said recesses.

3. An egg carrier comprising, in combination with a container, a plurality of frames adapted to be removably mounted in the container, each frame consisting of a plurality of substantially rectangular plates 70 provided with inwardly convergent recesses opening on two opposed edges, substantially parallel rods traversing said plates for holding them in connected relation with their recesses in alinement, sleeves loosely mounted on the rods for disposing the plates in spaced relation longitudinally of the rods, a plurality of elongated sacks disposed in said recesses to provide holders for the eggs between the plates, each of said sacks having 80 opposed edges defining an opening extending its entire length, and a latch pivotally mounted on each plate for making, in alternation, engagement and disengagement with the sacks in said recesses. 85

4. In an egg carrier, the combination of a container, a plurality of frames adapted to be removably mounted therein, each frame consisting of a plurality of plates provided with lugs and recesses, members traversing 90 the plates for holding them in connected relation, members interposed between the plates for maintaining them in spaced relation, a plurality of sacks disposed in said recesses to provide holders for the eggs between the plates, each of said sacks being provided at its ends with buffer-members disposed outwardly of the frame and having opposed edges defining an opening extending between said buffer members, latches 95 provided with recesses, each latch being adapted to have a swinging movement for engaging the lug of a plate, its recess engaging a sack in a recess of a plate. 100

5. In an egg carrier, the combination of a container, a plurality of frames adapted to be removably mounted therein, each frame consisting of a pair of end plates and intermediate plates, each plate being provided with recesses, a plurality of rods carried by the end plates and traversing the intermediate plates, sleeves disposed between said plates and carried by said rods, a plurality of sacks each having opposed edges extending between its ends, said sacks being adapted to be disposed in said recesses to provide holders therebetween for the eggs, latches provided with recesses mounted on said plates and adapted to have swinging movements inwardly thereof for engaging the sacks in said recesses and adapted to have outward swinging movements for disengagement with said sacks. 110 115 120

6. In an egg carrier, the combination of a container, a plurality of frames adapted to be removably mounted therein, each frame consisting of a plurality of plates provided with recesses opening on two opposed edges, substantially parallel rods traversing said plates for holding them in connected relation 130

with their recesses in alignment, sleeves loosely mounted on the rods for disposing the plates in spaced relation, a plurality of sacks disposed in said recesses to provide 5 holders for the eggs between the plates, each of said sacks having opposed edges defining an opening extending its entire length, and a latch pivotally mounted on each plate for making, in alternation, engagement and

disengagement with the sacks in said recesses.

In testimony whereof, I have affixed my signature in presence of two witnesses.

MARIE MELOTZ.
